DENTAL HANDPIECE

Walter S. Strauss, Williamsville, N.Y., assignor to Hanau Engineering Company, Inc., Buffalo, N.Y.

Filed Feb. 1, 1960, Ser. No. 59,222

Term of patent 14 years

(Cl. D24—1)

FIG. 1.

FIG. 2.

FIG. 3.

FIG. 1 is a front end elevational view of a dental handpiece showing my new design;

FIG. 2 is a side elevational view thereof; and

FIG. 3 is a rear end elevational view thereof.

The side not shown is substantially the same in appearance as the side shown.

I claim:

The ornamental design for a dental handpiece, as shown and described.
